UNITED STATES PATENT OFFICE

2,154,775

SIREN TOY

Jose A. Robles, Kansas City, Mo.

Application May 7, 1936, Serial No. 78,479

1 Claim. (Cl. 46—66)

My invention relates to toys and particularly to spinning tops, in which a siren effect is produced while the top is in motion, and it consists in the constructions, arrangements and combinations herein described and claimed.

It is an object of the invention to provide a top of hollow formation having an adjustable aperture in the wall thereof whereby the sound produced by rotation of the top may be varied.

It is also an object of the invention to provide a top in which a dual sound effect may be produced.

It is a still further object of the invention to provide means for readily manipulating the top.

Additional objects, advantages and features of invention will be apparent from the following description considered in conjunction with the accompanying drawing, wherein

Figure 1 is a perspective view of a top constructed in accordance with my invention;

Figure 2 is a top plan view thereof illustrating the approximate positions of the hands of the user.

Figure 3 is a fragmentary sectional view of the top, illustrating the valve.

Figure 4 is a plan view of a modified form of manipulating handle.

Figure 5 is a modified form of top, constructed for dual production of sound.

Attention is first invited to Figures 1 to 3 of the drawing, wherein there is shown a top, generally indicated at 10, of cylindrical form having end walls 11. The end walls 11 are centrally apertured and fixed rigidly therein is a spindle 12, one end 13 thereof extending only a short distance from the lower end wall 11, being suitably shaped to form the supporting pivot of the top during rotation. The opposite end 14 extends a greater distance from the upper end wall than the end 13 does from the lower end wall and forms in effect a drum portion upon which an actuating cord 15 is wound.

The cord 15 is provided with a handle member 16, adjacent one end of which there is formed an aperture 17 through which the cord is passed and knotted as at 18.

In the side wall of the top 10 there is formed an opening 19 extending in a longitudinal plane, of the top around three edges of which there are formed guide flanges 20. The upper edge of the guide flange is open, permitting the insertion of a sliding valve 21. The valve 21 is longitudinally adjustable in the flange 20, thus varying the amount of air which may be admitted through the uncovered portion of the opening 19. Obviously, the variance in the port opening will produce a difference in the siren effect of the top during rotation.

In Figure 5 a modified form of top is shown in which a dual sound effect may be produced.

In this form, the top is constructed as before described, but the interior of the top is provided with a horizontally disposed dividing wall 22, thus forming a pair of independent compartments 23 and 24. Each of the compartments 23 and 24 has an opening 25 and 26 respectively. The horizontal wall 22 is preferably disposed so that the chambers are of different sizes, and thus during rotation of the top two distinct sound effects will be produced, i. e., one might be quite shrill while the other will produce more or less of a bass effect.

In Figure 4 I have illustrated a modified form of handle which as shown, comprises the handle portion 27, including the aperture 28, adjacent one end. An open-ended bracket 29 is fixed to the handle 27 upon one side, shaped to embrace the end 14 of the spindle 12. In use, the open end of the bracket 29 will be presented around the spindle 12 and will amply support the top in an upright position when drawing upon the cord 15.

In use, the cord 15 is wound upon the portion 14 with the handle 16 or 27 (as the case may be), resting against the spindle. The cord is 25 then grasped by the knot 18 and drawn outwardly through the aperture 17 or 28. Such outward pull upon the cord will effect rapid rotation of the top, and by reason of the apertures 19 or 25—26, a siren effect will be produced.

The cord 15 may be wound upon the portion 14 from the bottom upwardly as shown in full lines in Figure 1, or may be wound from the top downwardly, in which event the handle 16 will be positioned closely above the top wall 11 as indicated by dotted lines.

The top and bottom walls have been illustrated as plane flat members, but obviously it is within the scope of the invention to form these walls in concave or convex form, if desired.

While I have shown and described a preferred form of the invention, this is for the purpose of illustration only, and I therefore consider as my own, all such modifications as fairly fall within the scope of the appended claim.

I claim:

A top of the character described including a hollow body member comprising side and end walls, said side wall having an elongated opening therein, one of said end walls having a top-supporting pivot member extending therefrom, a guide flange on said side wall bounding the sides of said opening and having an open end, an adjustable valve member slidably insertible in said guide flange through the open end thereof for varying the size of said opening, and means to effect spinning of said top for producing variable sound effects dependent upon the position of said valve relative to said opening.

JOSE A. ROBLES. 60
